United States Patent Office.

EDWARD P. WOODS AND DANIEL SHERWOOD, OF LOWELL, MASSACHUSETTS, ASSIGNORS TO WOODS, SHERWOOD & CO., OF SAME PLACE.

Letters Patent No. 70,770, dated November 12, 1867.

IMPROVED MACHINE FOR MAKING WIRE DISH-STANDS, &c.

The Schedule referred to in these Letters Patent and making part of the same.

TO ALL WHOM IT MAY CONCERN:

Be it known that we, EDWARD P. WOODS and DANIEL SHERWOOD, both of Lowell, in the county of Middlesex, and State of Massachusetts, have invented a new and useful Machine for Forming up Wire Dish-Stands, Egg-Boilers, &c.; and we do hereby declare the following to be a full, clear, and exact description thereof, reference being had to the accompanying drawings, figures and letters of reference thereon making part of this specification. Of the said drawings—

Figure 1 represents the machine in perspective.

Figure 2, a front view of the "former."

Figure 3, a sectional view of the same through the line *x y*.

Figures 4 and 5 are front and side views of the coil as formed on the machine.

Similar letters of reference indicate like parts in all the drawings.

Prior to the date of our invention, wire dish-stands, egg-boilers, &c., made of wire, wound in spiral form, and kept in proper place by being secured to framework cross-wires, were made by hand, being very imperfect and irregular, and the operation slow and expensive.

Our invention obviates these difficulties, and renders the process of manufacturing these and similar articles more quick, and the articles more perfect and symmetrical, while they can also be sold at a considerable less price than the hand-made article.

Our invention consists, first, in the employment of a cup-like disk, in the face of which is cut a groove to receive the wire; this groove commences at the centre of the disk, and constantly increases in the form of a spiral until it reaches the periphery, where it continues in the form of a helicoid, which will be fully described hereafter; second, in combining with a grooved disk a bar, which forces the wire into the grooves; third, in combining with a grooved disk a series of slots, whereby the operation of securing the spiral in its proper shape is greatly facilitated.

To enable others skilled in the art to make and use our invention, we will describe the construction and operation thereof.

A represents the base, and B the top, which are secured together by the two uprights C C in any suitable manner. F is the spirally-grooved disk or "former," secured to the mandrel D by the collar I. Back of the centre of the "former" is shown a bar, G, which is inserted in the slots *h h* in the frame, and held in place by the set-screws H H. The grooved "former" is made as follows: We first take the disk, which has been cast and finished of the proper shape and size, and secure it to the mandrel D. This is then mounted in a lathe, upon centres, having a tool-holder moved by a screw, and, by means of proper gearing, motion is imparted to the screw, and on the tool being brought in contact with the disk, a regular spiral groove is cut, constantly increasing in size until the bevel is reached. The continuation of the groove on the bevel is cut by means of regular screw-gearing. The groove is cut sufficiently deep to hold the wire, and slightly inclined towards the centre, to prevent the wire from springing out during the operation of applying the supporting frame.

Operation.

The bar G is removed from the frame, and the mandrel D is inserted in its journals, in the uprights C C, and the winch E secured to the end by the screw, as plainly shown in fig. 1. The bar G is then inserted in the slots *h h*, and set up sufficiently close by the screws H H to the "former" F, so as to force the wire into the grooves. The end of a piece of wire, *a*, is now inserted in the hole *e*, and the wire held by sufficient friction while the handle is turned by the operator, who guides the wire into its proper groove, and continues the operation until the required number of grooves is filled, when the end of the wire is "fastened off" at the pin *v*. But a few seconds are required in which to shape the wire for a dish-stand or egg-boiler. The winch is removed, and the "former" F taken out and set upright before the workman, who places the frame around the "former" F, and the legs on the face of the "former" and over the slots *c c*, and with fine wire quickly secures, by interlacing, the spiral bottom and sides with the frame. The article is then taken from the "former," and is ready to be turned.

Claims.

- We claim—
1. The spiral-grooved head or "former," constructed substantially as described and specified.
  2. The combination of the spiral-grooved head or "former" with the bar G, substantially as described and specified.
  3. The combination, with the spiral-grooved head or "former," of the slots *c c c*, substantially as described and specified.

EDWARD P. WOODS,
DANIEL SHERWOOD.
